To all whom it may concern:

Be it known that we, Walter K. Jahn and Charles L. Bonner, citizens of the United States, residing at Beverly Hills and Montauk Point, in the counties of Los Angeles and Suffolk and States of California and New York, respectively, have invented a new, original, and ornamental Design for a Tobacco Pipe Cleaner, of which the following is a specification, reference being had to the accompanying drawing, forming a part thereof.

Fig. 1 is a plan view of a tobacco pipe cleaner showing our new design.

Fig. 2 is a front elevational view of the pipe cleaner illustrated in Figure 1;

Fig. 3 is a rear elevational view of the pipe cleaner illustrated in Figure 1.

We claim:

The ornamental design for a tobacco pipe cleaner, as shown.

WALTER K. JAHN.
C. L. BONNER.
